UNITED STATES PATENT OFFICE.

BRUNO KANNENBERG, OF BERLIN-GRUNEWALD, GERMANY.

SHED FOR AIRSHIPS.

1,426,197.

Specification of Letters Patent. Patented Aug. 15, 1922.

Application filed February 19, 1921. Serial No. 446,478.

To all whom it may concern:

Be it known that I, BRUNO KANNENBERG, a citizen of the German Republic, residing at Berlin - Grunewald, 2 Franzensbaderstr., 5 Germany, have invented certain new and useful Improvements in Sheds for Airships (for which I have filed application in Germany May 30, 1919), of which the following is a specification.

10 The present invention relates to sheds for air ships, and particularly to a rotary shed not provided with a floor. In its preferred form, the shed rests on a plurality of ring rails so that it may be rotated in any direction necessary to permit the entrance or departure of the air ship. The invention contemplates especially a construction in which the longitudinal supporting members of the shed, instead of being interconnected 15 by the usual shed floor which is here lacking, are mounted on one or more rigid ring members, which are of greater diameter than the width of the shed and are carried in shallow circular canals. The smaller ring 20 also serves to support the shed against lateral wind thrusts or the like which are transmitted through the ring to the foundation.

In the accompanying drawings—

Fig. 1 is a vertical longitudinal section 30 through a shed, with two associated ring members;

Fig. 2 is a plan thereof;

Fig. 3 is a cross section through the shed, drawn to a larger scale and omitting the 35 outer ring;

Fig. 4 is a plan of portion of the inner ring;

Fig. 5 is a side element of one of the longitudinal supporting members of the shed;

40 Fig. 6 is a plan of the smaller ring; and

Fig. 7 is a section, on a larger scale, through this ring.

The present shed, in skeleton, comprises two longitudinal supporting members 1, the 45 roof frame 2, and the two lower longitudinal tie elements 8 which connect together the frame members and reinforce it against wind stresses. The longitudinal supporting members 1 have upper and lower girders 3 and 4 respectively, which are united by inclined struts 5 and vertical struts 6. The inclined struts 5 are connected to the foot pieces of the vertical struts 6 by means of intermediate struts 7. The wind braces 8 50 comprise horizontal members 9, which connect the foot pieces of the frame and are

supported from the uprights by inclined bars 10. The latter is stiffened by the struts 11 and 12 extending respectively to the horizontal frame 9 and to the foot pieces of the 60 main frame.

The longitudinal supporting members 1 are supported toward their opposite ends by depending posts 13 on trucks 14, provided with four or more wheels, which run on circular tracks 15. Similarly toward their mid areas, the longitudinals 1 are provided with other depending posts 16 resting on trucks 17, the wheels of which also run on a circular track 18. At the ends of the shed are 70 sliding doors 19, which rest on a circular runway 20. In Fig. 2 the door at the left-hand end of the figure is shown closed, while that at the right end is open.

The side walls of the shed are rigidly supported with relation to each other by two rigid flat rings 21 and 23, which are accommodated in two circular canals 22 and 24. The smaller inner ring 23 is connected to the side frames 1 of the shed at the points 30, 80 31, 32 and 33. In as much as the rings lie below the surface of the ground, the connecting members must extend downward into the canals for the rings. For this purpose special struts 25 and 26 (Fig. 5) are 85 provided at the points of connection, from which the single connecting post 27 extends down into the canal. The lower end of the post, which at 30 is connected to the ring 23, is supported by the inclined struts 28 90 and 29 (Figs. 3 and 5) extending in planes at right angles to each other. In the same manner, connection is made between the longitudinals 1 and the inner ring 23 at 31, 32 and 33, and the outer ring 21 at 34, 35, 95 36 and 37.

The inner ring and outer ring are both formed by lattice work frames, and carry wheels 38 (Fig. 7) which run on tracks 39 laid on the bottoms of the canals 24. The 100 frame of the inner ring 23 at the four diametrically opposite points 40, 41, 42 and 43 is connected by bars 44 with a link chain 45. Horizontal rollers 46, mounted on this chain, bear against circular rail 48, which is embedded in the vertical side wall 49 of the canal 24. The sections of the chain to which the posts 44 are attached constitute half links 47. This arrangement prevents any cross strains at these points, and insures 110 stresses only in the direction of the length of the chain. The wind stresses on the shed

are consequently transmitted through the ring 23 on a tangent to the roller chain, so that the rollers on one half the chain are simultaneously placed under equal pressure. If, 5 for instance, as indicated by the arrow in Fig. 6, the wind comes from the left, the stresses are exerted at the points 41 and 43 on the roller chain, so that the half of the chain on the windward side of the shed is 10 placed under tension, while the half on the lee side is slack. In this manner the wind pressure is distributed over a full half of the foundation ring,—a considerable span—and a full half of the chain takes the strain. 15 By reason of this distribution of the stresses over the entire half of the ring foundation, the latter may be made relatively light.

The canals may be covered over by platforms 50 carried by the rings and rotating 20 with them. These platforms prevent the choking of the canals with dirt or snow, and thus keep the structure in operative condition.

Where the shed is relatively short, a single ring suffices to afford the necessary rigidity to the structure. If the shed is of 25 greater length, more than two rings may be used if necessary or advisable.

I claim as my invention—

30 1. A rotary shed for air ships, comprising a pair of horizontal side frames, and ring means having a diameter at least equal to the width of the shed, and to which the side frames of the latter are connected, said 35 ring means constituting tie means by which the side frames of the shed are united, substantially as and for the purpose set forth.

2. A rotary shed for air ships, comprising a pair of horizontal side frames and a plurality of concentric rings, certain of which 40 are of greater diameter than the width of the shed, and to which the sides of the latter are connected, said rings constituting the tie means by which the side frames of the 45 shed are united, substantially as and for the purpose set forth.

3. A rotary shed for air ships, comprising a pair of horizontal side frames, and sub-surface ring means having a diameter at

least equal to the width of the shed, and to which the side frames of the latter are connected, said ring means constituting tie means by which the side frames of the shed are united, substantially as and for the purpose set forth. 50

4. A rotary shed for air ships, comprising a pair of horizontal side frames, and sub-surface ring means having a diameter at least equal to the width of the shed, and to which the side frames of the latter are connected, said ring means constituting tie means by which the side frames of the shed are united, together with a platform carried by the ring means at ground level, substantially as and for the purpose set forth. 55

5. A rotary shed for air ships comprising a pair of horizontal side frames, and a ring of greater diameter than the width of the shed, and to which the sides of the latter are connected for the purpose specified, together with a roller chain operatively associated with said ring and an abutment against which said chain bears to take up lateral stresses on the ring. 60

6. A rotary shed for air ships comprising a pair of horizontal side frames, and a ring of greater diameter than the width of the shed, and to which the sides of the latter are connected for the purpose specified, in combination with a sub-surface circular 75 canal in which said ring is accommodated, together with a roller chain located in said canal and bearing against a side wall thereof, and means connecting said chain and ring together. 80

7. A rotary shed for air ships comprising a pair of horizontal side frames, and a ring of greater diameter than the width of the shed, and to which the sides of the latter are connected for the purpose specified, together with a link roller chain operatively 90 associated with said ring, and a link connection between the chain and ring for the purpose described.

In testimony whereof I have signed my name to this specification. 95

BRUNO KANNENBERG.
